UNITED STATES PATENT OFFICE

LEVI HAWBAKER, OF ELMORE, MINNESOTA

WIRE STRETCHER

Application filed August 29, 1927. Serial No. 216,055.

This invention relates to a wire stretching and splicing device, and while the device has utility for stretching and splicing wires in any desired location, it is especially useful in 5 tightening wires used on fences.

It is an object of this invention to provide a simple and efficient wire stretching device and one which can be easily operated and produced at small expense.

10 It is another object of the invention to provide a wire stretching device comprising a pair of hingedly connected curved members having laterally projecting abutment members with surfaces which incline inwardly, 15 together with handle bars pivoted to said members having end surfaces co-operating with said surfaces whereby the natural movement of the wire being manipulated will be inwardly of the gripping surfaces.

20 These and other objects and advantages of the invention will be fully set forth in the following description made in connection with the accompanying drawings, in which like reference characters refer to similar parts 25 throughout the several views and in which:—

Fig. 1 is a view in front elevation of the device, a portion thereof being broken away;

Fig. 2 is a view in side elevation of the device as seen from the right of Fig. 1;

30 Fig. 3 is a vertical section taken on line 3—3 of Fig. 1 as indicated by the arrows;

Fig. 4 is a view illustrating the operation of the device;

35 Fig. 5 is a view illustrating the operation of the device in a further step than shown in Fig. 4;

Fig. 6 is a view also illustrating the further step in the operation of the device than that shown in Fig. 5; and

40 Fig. 7 is a view illustrating a different operation of the device.

Referring to the drawings, a device is shown comprising a pair of curved arms 10 having circular end portions hingedly connected in overlapped relation by the pivot rivet 9. The arms 10 as shown in Fig. 1 normally diverge from each other and the same are provided at the same side of the device with projections 10^a. These projections have 45 abutment surfaces 10^b which are directed

away from the pivot 9 and extend to the outer edge of the abutments 10^a. It will be noted that the surfaces 10^b slope inwardly in a direction toward the pivoted end of the device when the same is in the position shown in Fig. 1, so that the said surfaces 10^b as illustrated make an angle somewhat less than a right angle with the surface 10^c which extends beyond the abutment or projection 10^a. The arms 10 each have pivoted thereto beyond the projection 10^c, bars 11 which are of considerable length and adapted to form handles at their free ends, said bars being pivotally connected to the members 10 by the pivots 12. The ends of bars 11 are formed with curved surfaces 11^a of convex form, which curve inwardly of the device and are adapted to move close to and co-operate with the surfaces 10^b in gripping a wire. It will be seen that the surfaces 11^a also terminate at the outer surfaces of the bars 11, so that an open-ended slot or opening is formed between the surfaces 10^b and 11^a, as clearly shown in Figs. 1 and 3. One of the members 11 has an aperture 11^b at one end, in which is received the end link of a chain 13, which chain is free at its other end and one of the links of which is adapted to be hooked over a hook portion 11^c formed at the end of the other bar 11.

55 The device may be used to splice or tighten 60 wires in various ways. When the wire has a little slack and is old and brittle, the method shown in Figs. 4, 5 and 6 is used. The device is opened as shown in Fig. 4 and the wire 14 engaged between the surfaces 10^b and 11^a of each of the arms 10 and 11. The bars 11 are then swung towards each other and the wire is gripped between said surfaces as the bars move inward toward each other, the wire 14^a is stretched. A bight or loop 14 is 65 formed between the arms 10 and bar 11 as shown in Fig. 5 chain 13 being engaged over hook 11^c to hold the tension. A short length of wire 15 is then twisted about the wire 14 at one side of the device, as shown in Fig. 5, and the other end of this wire is then carried across the device and twisted about the wire 14 at the other side of the device as shown in Fig. 6. This wire can be readily 70 twisted and manipulated by an ordinary pair 75 of pliers.

80 85 90 95 100

of pliers such as shown at 16 in Figs. 5 and 6. When the wire 15 is twisted about the wire 14 at both sides of the device, the handle of the pliers is inserted between the wire 15 and the loop 14^a as shown in Fig. 6, and these two twisted together. The wire 14 is thus tightened, and is held in tightened condition by the wire 15. When a wire is gripped between the surfaces 10^b and 11^a and placed under tension, the wire tends to shift between said surfaces. If the surfaces 10^b extend horizontally or at right angles to surface 10^c, the wire would be just as apt to slip outwardly and often shifts out of the device. By having the surface 10^b inclined as shown in Fig. 3, the wire shifts inwardly between surfaces 10^b and 11^a and becomes disposed in the corner between surfaces 10^b and 10^c. A sure grip is thus assured on the wire between the surfaces 10^b and 11^a.

Another form of splice is shown in Fig. 7. This method is used when there is considerable slack in the wire. The wire is clamped in the device as shown in Fig. 4 and the bars 11 pulled together to form a loop as shown in Fig. 5. This loop will hold the small slack and the stretching operation is repeated one or more times. When the wire is sufficiently tensioned, the chain 13 is engaged over the hook 11^c by one of its links and the tension retained on the wire. The loop portion of the wire is then cut close to one clamp, for instance five or six inches therefrom. The long end is then bent and twisted around the taut wire outside of the clamp as shown in Fig. 7. The short end is then twisted around the wire inside of the clamp 6, as shown in said figure, and the ends of the wire can be cut off as desired.

To tighten wires at posts, one end of the wire is engaged between one of the surfaces 10^b and the corresponding bar 11 and the arm 10 adjacent its pivotal point is then rested against the post, and the bar 11 gripping the wire is swung about the point of engagement with the post so that the bar 11 and arm 10 act as a lever to tighten the wire. After the wire is sufficiently tightened, it is secured to the post by a staple or other well known means.

From the above description it is seen that applicant has provided an extremely simple and very efficient wire stretching device and one which can be easily and quickly operated. It will be noted that the opening between surfaces 11^a and 10^b is open at its outer side or in other words, that there is no member overlapping this opening. In tools having a member overlapping the opening in which the wire is secured, it is difficult to release the wire after the same is spliced as shown in Figs. 6 or 7. In the present tool, the same is merely opened and moved laterally, thus quickly releasing the wire. The inclined surface 10^b as above described insures that the

wire will shift inwardly and be in position to be securely gripped. The device has been amply demonstrated in actual practice and found to be very successful and efficient, and the same is being commercially marketed.

It will, of course, be understood that various changes may be made in the form, details, arrangement and proportions of the parts, without departing from the scope of applicant's invention, which, generally stated, consists in a device capable of carrying out the objects above set forth, in the novel parts and combinations of parts disclosed and defined in the appended claims.

What is claimed is:—

1. A wire stretching device having in combination, a pair of arms pivotally connected together at one end and extending in diverging relation, said arms having laterally extending projections thereon at the same side of said device, said projections each formed with a surface facing away from the connected ends of said arms and with a surface intersecting said surface at the outer side of said projections, said first mentioned surface also inclining inwardly toward the connected end of said arm, a bar over-lapping and pivoted to each of said arms beyond said projections and having an inclined end surface adapted to substantially abut and cooperate with said first mentioned surface on said projection to clamp a wire therebetween, said surfaces forming a slot therebetween open at one side of said device, the ends of said bars being formed as handles.

2. The structure set forth in claim 1, said first mentioned surface on said projection being inclined to the central axis of said arms and outwardly from the adjacent sides of said arms, said surfaces on said bars being convex and also inclined outwardly.

3. A wire stretching device, having in combination, a pair of arms having straight portions and having ends curved toward each other and oscillatably connected by a pivot, said arms having flat surfaces at one side thereof, a lug projecting from the side of each arm adjacent said flat surface, said lugs having outer flat surfaces disposed substantially perpendicular to the axis of said pivot, said lugs also having surfaces extending to the sides of said arms and inclined inwardly on the respective arms toward said pivot, said latter surfaces also being inclined toward the axis of said pivot so as to form an acute angle with said flat surfaces of said arms, a bar having a flat surface over-lying the flat surface of each arm and pivoted to each of said arms some distance from said lugs on the side remote from said pivot, said latter bars having end surfaces inclined inwardly toward the sides of said pivot and adapted to swing into engagement with the inclined surfaces of said lugs, said latter arms also having outer surfaces substantially perpendicular to the axis of said pivot.

lar to the axis of said pivot whereby an open-ended slot is formed between said lugs when said latter bars are swung about their pivots so that a wire can be moved laterally between said lugs and clamped therebetween, the outer ends of said latter bars forming handles.

In testimony whereof I affix my signature.
LEVI HAWBAKER.
